UNITED STATES PATENT OFFICE.

WILLIAM A. FAGAN, OF SAN FRANCISCO, CALIFORNIA.

DOOR-RELEASER.

SPECIFICATION forming part of Letters Patent No. 761,290, dated May 31, 1904.

Application filed January 12, 1904. Serial No. 188,692. (No model.)

To all whom it may concern:

Be it known that I, WILLIAM A. FAGAN, a subject of Great Britain, residing in the city and county of San Francisco, State of California, have invented certain new and useful Improvements in Door-Releaseers; and I do hereby declare the following to be a full, clear, and exact description of the same.

The present invention is designed for use in connection with flats or apartment-houses or houses wherein it is desired to release the lock-catch of the front door or outer door from a distant point, the object being to provide against the necessity of having to travel from a distant point or to descend the stairs for the purpose of releasing the outer door in order that the same may be opened for a person desiring admission, the invention residing in the means whereby the door-catch is mechanically released and the door slightly opened from a distant point through the medium of a system of crank-levers and wire connections.

To comprehend the invention, reference should be had to the accompanying sheet of drawings, wherein—

Figure 1 is an inside view of an ordinary door, the door-casing being partly broken away and sectioned in order to illustrate the location of the releasing device and the opener, together with the connections for the operation of said devices. Fig. 2 is a vertical sectional end view of the casing, illustrating the position of the releaser and the opener. Fig. 3 is an enlarged broken detail view of the door, the casing being in vertical section. Fig. 4 is an enlarged detail view of the releaser viewed from the opposite side from that disclosed by Fig. 3 of the drawings, and Fig. 5 is an enlarged detail view in end elevation of the opening device for the door.

The numeral 1 designates an ordinary outer door for a house, and 2 the casing therefor, to which the door is hinged.

Within the side 2' of the casing is fulcrumed the lever 3, which is connected to the fulcrumed crank-lever 4 by the connecting-wire 5. This lever in turn is also connected to the fulcrumed crank-lever 6 by the wire 7.

The crank-levers 4 and 6 are arranged within the door-casing 2 above the door 1, Fig. 1 of the drawings, the levers being fulcrumed, re-

spectively, to the pillars 4' 6'. The opposite arm of the crank-lever 6 is connected by wire 8 to one end of the longitudinally-movable releasing-bolt 7', which bolt works through the catch-opening of the lock-plate 8', fitted within the side 3' of the casing 2, Figs. 1, 3, and 4 of the drawings. The releasing-bolt 7' is held in place by means of the screw-stud 8", which stud passes through a slot 9 cut in the said bolt and screws into the lock-plate 8'. The lock-plate 8' is formed with an inclined shoulder 9', upon which bears and rides a roll 10, secured to one face of the slide-releasing bolt 7', Figs. 3 and 4 of the drawings. The outer or free end of the releasing-bolt 7', when the door 1 is closed, bears against the door-catch 10'. By this construction it is obvious that as the inner end of the slide-bolt 7' is drawn upward the roll 10 working upon the face of the inclined shoulder 9' will force the said slide-bolt outward at an inclination. As thus moved the pressure of the releasing-bolt against the door-catch 10' will force the catch outward beyond the catch-opening of the lock-plate 8' or back into the lock, thus releasing the locked door and leaving same free to be opened by pulling upon the door-knob 11. So long as the upward or pulling strain continues on the wire 8 to maintain the releasing-bolt moved outward the door will be held released. It will be understood that the stud 8" acts as the fulcrum for the slide-releasing bolt 7'.

To indicate that the door is released, an opener is provided which will force outward the door a slight distance the moment the lock-catch has been released. This device is operated mechanically by the movement of the releasing-bolt and is so constructed as to remove all strain from the door when closed. The opening device is located within the side 3' of the door-casing, near the bottom thereof, a short distance below the releaser. It comprises a bell-crank lever 12, which is fulcrumed to a stud 12', projecting from a plate 13, fitted within one side of the door-casing 2. This crank-lever is normally held pressed inward by the tension of the spring 13', secured to and coiled upon the stud 12', one end of the spring bearing against a pin 14, projecting from the crank-lever 12. The crank-lever 12 swings transverse of the casing, the roll 14'

carried thereby working within a transverse slot 15 cut in the face of the plate 13. The projecting end of this roll when the crank-lever is inward its full distance, fits within a 5 socket or recess 15' cut in the rabbet 16 of the door-casing. Said roll rests against a bearing-plate 16', secured to the edge of the door, so that the pressure of the roll upon the door during the opening thereof will not injure the 10 surface of the woodwork.

The described device is actuated to open the door as the door-catch is released by the upward pulling strain exerted upon the wire 17, forming connection between the releasing-bolt 7' and the bell-crank lever 12, acting to 15 swing the crank-lever 12 outward transversely, causing the projecting roll 14', bearing against the edge of the door, to gradually force the door open a slight distance as the 20 roll is thrown outward within the slot 15 of the plate 13. As the pulling strain which actuates to operate the releasing-bolt ceases the tension of the spring 13' forces the crank-lever 12 inward or in a reverse direction, so as 25 to restore the same to its normal or closed position. This movement of the crank-lever 12 exerts a downward pull upon the wire 17 in order to draw the releasing-bolt 7' inward or 30 restore it to its normal position. At the same time the tension of the spring 17', which forms a connection between the crank 6 and the door-casing, Figs. 1 and 2 of the drawings, restores the lever 3 and cranks 4 and 6 and their 35 connections to normal position. When the parts are thus restored to their normal position, the door 1 is free to be closed, which may be done automatically or otherwise. In the present case an ordinary pneumatic door-closer 18 is employed to close the door. However, the 40 feature of closing the door forms no portion of the present invention. Hence no consideration need be given thereto.

The described mechanism for releasing the door-catch and opening the door is operated 45 by means of the wire 18'. One end of this wire is attached to the lever 3, Fig. 1 of the drawings, its opposite end terminating at whatever distant point from which it is desired to operate the releasing and opening mechanism. 50 This wire 18' for the purpose of the present case shall be termed the "main house-wire," meaning thereby the wire to be actuated from any fixed distant point within the house by the person desiring to operate the mechanism 55 to release and open the door.

Having thus described the invention, what is claimed as new, and desired to be protected by Letters Patent, is—

1. The combination with a door, of an inwardly-movable slide-bolt for actuating the lock-catch thereof to release the door, devices for causing the slide-bolt to travel at an inclination to the lock-catch of the door, a transversely-movable device for partly opening 60 the door so released, connection between the 65

releasing slide-bolt and the opening device by which the opener is positively actuated with the movement of the releasing slide-bolt to release the lock-catch, and connections between the releasing slide-bolt and a distant 70 point for operating the said slide-bolt and its connected device to release the door and open the same.

2. A door releasing and opening mechanism, the same comprising a longitudinally-movable 75 releasing-bolt for acting against the lock-catch of the door, devices for causing the releasing-bolt to travel at an inclination during longitudinal movement thereof to release the lock-catch, a transversely-movable device for 80 opening the door when released, connection between the releasing-bolt and the opening device for the door so that the releaser and opener operate substantially simultaneously, a house-wire actuated from a distant point, 85 connection between the house-wire and the releasing-bolt, and means for restoring the parts to their normal position when the house-wire is released.

3. A door releasing and opening mechanism, 90 the same consisting of a longitudinally-movable releasing-bolt, devices for causing the same to travel at an inclination during the longitudinal movement thereof, a house-wire operated from a distant point, connection between the said wire and the releasing-bolt, 95 and means for restoring the parts to their normal position when the house-wire is released.

4. In a releaser for doors, the combination 100 with the door-casing, a lock-catch plate fitted therein, a releasing-bolt slidably connected to said plate, a roll carried by the bolt, an incline surface on the plate upon which the roll of the bolt works to move the same outward, a house-wire, connections between said wire and 105 the releasing-bolt, and means for restoring the parts to their normal position when the house-wire is released.

5. In a releaser and opener for doors, the combination with the door-casing, a lock-catch plate fitted therein, a releasing-bolt slidably connected to said plate, a roll carried by the bolt, an inclined surface on the plate upon which the roll of the bolt works to move the same outward, a transversely-movable device 110 for opening the door when its lock-catch is released, said device bearing against the door when closed, connection between the opening device and the releasing-bolt, a house-wire, 115 connections between the house-wire and the releasing-bolt, and means for restoring the parts to their normal position when the house-wire is released.

In witness whereof I have hereunto set my hand.

WILLIAM A. FAGAN.
